United States Patent Office.

JOHN THOMPSON, OF HARTVILLE, OHIO.

Letters Patent No. 66,416, dated July 2, 1867.

CHURNING APPARATUS.

The Schedule referred to in these Letters Patent and making part of the same.

TO ALL WHOM IT MAY CONCERN:

Be it known that I, JOHN THOMPSON, of Hartville, in the county of Stark, and State of Ohio, have invented a new and useful Apparatus for Churning; and I do hereby declare that the following is a full, clear, and exact description of the same, reference being had to the accompanying drawings, and to the letters marked thereon, of which—

Figure 1 is a side view of the apparatus, showing its application to a churn.

Figure 2 is a plan of the same.

Figure 3 is an end view of the same.

The nature of my invention consists in the peculiar arrangement and combination of a double crank-shaft with two churn-dashers, by means of working-beams and connecting-rods, in such a manner as that by rotating the double crank-shaft, the dashers shall alternately move up and down, the said double crank-shaft being operated by gearing, which receives motion from a cord wound around a drum, and passing over a pulley hung to the ceiling, with a heavy weight at its end; and also in so hanging one end of the axle of the main drum or pulley in a lever as that, by raising the lever, the first wheel may be disengaged from the first pinion, in order to allow of winding up the weight.

To enable others skilled in the art to make and use my invention, I will proceed to describe its construction and operation.

A is a plank or frame, forming the bottom or foot of the machine. In the bottom A are framed the uprights B B and the standard C. a is an axle, one end of which is placed in a bearing in the upright B, the other end passing through a slotted hole, g, in the upright B, and supported in a bearing in the lever f. On this axle a is the pinion K and the drum T. The cord S is wound around the drum T, and passed over a pulley, X, hung to some elevated point, and has a weight, W, attached. The wheel K gears into the pinion L on the axle b, giving motion to the wheel M on the same axle, which gives motion to the pinion N on the axle C, which gives motion to the wheel O on the same axle, which, in turn, gives motion to the pinion p on the double crank-shaft Q. The double crank-shaft Q is connected to the working-beams D and E by the connecting-rods R and S, and the working-beams D and E are connected at their other extremities with the dashers G and F of the churn H. The working-beams D and E are hung on the bolt V, at the upper part of the standard C, the distance from the bolt V and dashers G and F being varied by means of the different holes in the working-beams D and E, so that the vertical motion of the dashers G and F may be regulated to suit the quantity of cream in the churn. The lever f is held down by the pin h, and by removing the pin h the action of the cord S and weight W raises the end d of the axle a, so that the wheel K is thrown out of gear, when by applying, as shown in fig. 3, the cord S, can be wound up.

I do not claim as my invention the wheels K, M, and O, pinions L, N, and p, axles a, b, and C, dashers F and G, but what I do claim as my invention, and desire to secure by Letters Patent, is—

The use of the double crank-shaft Q, in connection with the connecting-rods R and S, and working-beams D and E, when said crank-shaft is operated by wheel-work, cord, and weight, in the manner and for the purpose herein specified.

As evidence that I claim the foregoing I have hereunto set my hand in the presence of two witnesses.

Witnesses:

JOB ABBOTT,
E. N. BEEBOUT.

JOHN THOMPSON.
